UNITED STATES PATENT OFFICE

HANS LUND, OF BERLIN-SCHONEBERG, HANS LAUB, OF BERLIN-TEGELAND, AND FRANZ HIRT, OF BERLIN-FRIEDENAU, GERMANY, ASSIGNEES TO GENERAL ELECTRIC COMPANY, A CORPORATION OF NEW YORK

SIGNALING SYSTEM

Application filed September 30, 1927, Serial No. 223,223, and in Germany January 5, 1927.

Our invention relates to signaling and control systems and more particularly to systems adapted for the transmission of signals from stationary points to a moving vehicle. Still 5 more particularly our invention relates to systems of the type described in Patent No. 1,699,377 entitled Electric train control, issued May 8, 1928, to Hans Lund and Hans Laub, and which is assigned to the same assigee as our present application.

In the above mentioned copending application a primary electrical circuit is mounted upon a train and a secondary circuit is mounted upon the track and positioned to 15 be in inductive relation with the primary circuit, and adapted to produce current variations therein as the train passes over the track. If a variable frequency is impressed upon the primary circuit when the said circuit is in inductive relation with the secondary circuit both current diminutions below a normal value and current increases 20 above a normal value will occur in the primary circuit dependent upon the frequency. Likewise, if the frequency is maintained constant a similar result may be produced by varying the constants of the secondary circuit.

The purpose of our invention is to provide 25 means whereby either a current diminution or a current increase in the primary circuit may be utilized for the purpose of operating a desired signal or control device. Still a further purpose of our invention is to provide means including an electron discharge device whereby a device operated responsive to such current increase, or diminution, may be maintained in its operated condition.

40 In carrying our invention into effect we utilize a phenomenon, which is already known in connection with electron discharge devices, of the so-called "glow tube" type, that when a potential impressed across the terminals of this discharge device is increased to a certain fairly definite value the device will suddenly break down and current will flow between its electrodes. Having thus been broken down the impressed 45 potential may be reduced to a fairly definite

lower value where the discharge will cease. Thus, for example, if a 110 volt glow tube is employed it will be found that the device will be caused to glow at a voltage of about 90 volts, whereas if this voltage is reduced 55 the tube will cease to glow at a value of about 80 volts. Thus if a normal polarizing potential of, for example, 85 volts is impressed upon the device it will not glow until this potential has been increased to a value of, or 60 above, 90 volts after which it will continue to glow until this voltage has been reduced to a value of, or below, 80 volts. This higher voltage, at which the device is caused to break down or to permit current to flow, we shall 65 hereafter refer to as the discharge voltage of the device, and the lower voltage at which the discharge ceases we shall hereafter refer to as the extinction voltage of the device.

In accordance with our invention we utilize 70 this phenomenon in connection with the system described in the above mentioned application in a manner such that a more reliable operation of the relay, or signaling device, to be operated is produced, and further 75 in a manner such that after said device has been once operated in response to a current impulse, or diminution, in the primary circuit it will be maintained in its operating condition.

The novel features which we believe to be 80 characteristic of our invention will be set forth with particularity in the appended claims. Our invention itself, however, both 85 as to its organization and method of operation, together with further objects and advantages thereof, may best be understood by reference to the following description taken in connection with the accompanying drawing in which Fig. 1 represents one embodiment of our invention and Fig. 2 represents a modification thereof.

With reference to Fig. 1 of the drawing, 90 1 represents an alternating current generator which is mounted upon a train and adapted to supply alternating current through a circuit including a primary winding 2 of a transformer 3 and inductance coil 4. 5, 6 and 7 represent respectively an inductance, a 95 capacitance, and a switch which are connected 100

in a closed circuit mounted upon the track. The inductance coils 4 and 5 respectively constitute the primary and secondary winding of a transformer, the coil 4 being mounted upon the train and the coil 5 being mounted upon the track and so positioned as to be in inductive relation with the coil 4 when the train passes over the track. The switch 7 is adapted to close the circuit of the inductance 5 and condenser 6 in accordance with desired signals, as set forth in the above mentioned application. It will thus be seen that with a certain adjustment of the condenser 6 and inductance 5 a current increase will be produced in the primary winding of the circuit 1, 2, 4 as the train passes over the track, whereas with a certain different adjustment of the condenser 6 and inductance 7 a diminution of the current normally flowing in the circuit 1, 2, 4 will be produced. 8 represents the secondary winding of the transformer 3 which is connected through the blocking condenser 9 across the terminals of an electron discharge device 10. This device 10 is preferably of the usual glow tube construction comprising a vessel containing an inert gas, such as neon or argon, and having electrodes spaced apart in the vessel in a manner such that current passes between them when the voltage is sufficiently increased. The construction of these devices is well-known in the art and need not be further set forth here. 11 comprises a source of potential which is connected through a switch 12 and the actuating coil of a relay 13 to the opposite terminals of the discharge device 10. The source of potential 11 is such that with the switch 12 in its closed position a potential having a value intermediate the discharge value and extinction value of the discharge device 10 will be impressed upon the device.

As thus constituted if a current increase is occasioned in the circuit 1, 2, 4 as the coil 5 passes into inductive relation with the coil 4 a potential will be supplied across the terminals of the device 10 with the result that this device will break down and current will then flow from one terminal of the source of potential 11 through the switch 12, space between the anode and cathode of the device 10, and winding of the relay 13 back to the opposite side of the source 11. The relay 13 will thus be caused to operate thereby to actuate any desired signal or control apparatus. After the train has passed the secondary circuit and the current of the primary circuit has been reduced to its normal value only the voltage of the source 11 will be impressed upon the device 10 but the device will continue to glow and maintain the relay 13 in its operated condition until the discharge of the device 10 is extinguished by the operator.

If it be desired to utilize current decreases which may occur in the primary circuit a compensating winding 14 upon the trans-

former 3 may be employed, this winding being energized in opposed relation to the winding 2 with respect to the secondary winding 8. Thus, for example, if the winding 14 and the winding 2 have an equal number of turns and are equally energized no voltage will be produced in the winding 8 with the result that either an increase or a decrease of current in the winding 2 will produce an increase of voltage in the winding 8. Likewise, if a greater current normally flows in the winding 14 than in the winding 2 a decrease of current in the winding 2 will produce an increase of voltage in the winding 8, whereas an increase of current in winding 2 will produce a lesser effect dependent upon the relative magnitude of the two currents. The value of the current flowing in winding 14 may be adjusted by inductance 18 which, for complete compensation, should be just equal to the inductance of the transformer 4, 5.

In Fig. 2 we have shown a modification of our invention in which the structure 15 serves the purposes of both the transformer 3 and the relay 13. This structure comprises a U shaped magnetic core having wound thereon the primary 2, secondary winding 8 and the compensating winding 14. In this case the alternating current generator 1 supplies alternating current to the primary circuit constituted by the winding 2 and the coil 4, and also supplies polarizing potential to the discharge device 10 through the secondary winding 8. The compensating winding 14 is connected directly across the terminals of the generator 1. Pivoted at a point intermediate the open ends of the U shaped member is an armature 16 which is adapted when the core is energized to engage the contacts 17 which may be connected in any suitable electrical circuit. Coil 5 is positioned on the track in inductive relation with the coil 4 and current increases, or diminutions, as the case may be, will be produced thereby in the primary circuit, thereby energizing the core member and causing the armature 16 to engage the contacts 17 and the discharge device 10 to break down. The device 10 having broken down will maintain the magnetic core energized and the armature 16 in its actuated position.

While we have particularly mentioned the use of the device 10 as a means for retaining the relay, or other signaling or control device in its operated condition it, of course, will be apparent that it possesses marked advantages in that in response to a small change in current in the primary circuit a comparatively large current may be caused to flow through the windings of the signaling device. Likewise, while we have particularly mentioned the use of the glow tube as a normally inactive device which discharges current in response to a current variation

in the primary circuit, it will, of course, be understood that we do not wish to be limited thereto since the device may be normally in its discharge condition and caused to cease its discharge by current variations in the primary circuit, thereby to actuate a signaling, or control device.

The use of the compensating winding on the transformer produces marked advantages in the operation of the system in that it substantially compensates the effect of leakage reactance in the transformer to thereby increase the possible current variations in the primary circuit. Its use also permits of a larger percentage increase in voltage in the secondary winding. If desired two transformers may be employed, one of these being adapted to produce secondary voltage increases in response to a current diminution in the primary circuit, and the other in response to a current increase in said circuit. Thus it is possible to transmit two signals practically simultaneously, one a main signal and the other an auxiliary signal.

25 While we have shown and described a particular embodiment of our invention it will, of course, be understood that we do not wish to be limited thereto, since many modifications may be made, both in the circuit arrangement and in the instrumentalities employed without departing from the spirit and scope of our invention as set forth in the appended claims.

What we claim as new and desire to secure 35 by Letters Patent of the United States, is:—

1. In combination, an electrical circuit, means whereby a current variation is caused therein, means adapted to be operated responsive to said current variation, means for retaining said means in its operated condition after said variation has passed, said retaining means including a normally inactive electron discharge device and means responsive to said current variation for causing said device to 45 become active.

2. In a train signaling system, a primary circuit mounted upon a train and connected to a source of alternating current, a secondary circuit mounted upon the track and positioned to be in inductive relation to said primary circuit and adapted to vary the current flowing therein when said train passes over the track, an auxiliary circuit, a transformer having a winding connected in said primary circuit, a winding connected in said auxiliary circuit and a compensating winding, means adapted to be operated in accordance with voltage variations on said secondary winding and means including an electron discharge 55 device for retaining said last means in its operated condition.

3. In a railway signaling system, a primary circuit mounted upon a vehicle and energized from a source of alternating current 60 carried by the vehicle, a secondary normally

deenergized circuit positioned upon the track in inductive relation with the primary circuit when the vehicle passes over the track and adapted by the circulating currents induced therein by the primary circuit to vary the current flowing in the primary circuit 70 when the vehicle passes the secondary circuit on the track, means arranged to be operated from one position to a different position in response to said variation, and means including an electron discharge device for retaining said means in said different position independently of said source after the secondary circuit is passed.

4. In a train signaling system, a primary circuit mounted upon a train and connected to a source of alternating current, a secondary circuit mounted upon the track and positioned to be in inductive relation to said primary circuit and adapted to vary the current flowing therein when said train passes over the track, an auxiliary circuit coupled to said first circuit including an electron discharge device having a certain discharge voltage, a lesser extinction voltage and polarized at a potential intermediate said two voltages said device being adapted to discharge responsive to said current variations, and means adapted to be operated responsive to current flowing through said device resulting 85 from said discharge.

5. In combination, an alternating current circuit, a second circuit adapted for relative movement with respect thereto to produce a current diminution in said first circuit, a transformer having a primary winding, a secondary winding and a compensating winding, said primary winding being connected in said first circuit and so energized with respect to said compensating winding that a current diminution in said primary winding produces a voltage increase in said secondary winding, means adapted to be operated responsive to said voltage increase and means including an electron discharge device for retaining said means in its operated condition.

6. In combination, an electrical circuit, means for producing current variations therein, an electron discharge device, a source of polarizing potential for said discharge device of a certain value, said device being adapted on a certain variation of potential above said value to discharge and, on a certain variation of potential below said value, to extinguish said discharge, means adapted to be operated in response to a discharge in current through said device, and means for impressing a varying potential on said device exceeding one of said certain variations.

7. In combination, an electrical circuit, a core comprising a normally open magnetic circuit, an armature in said magnetic circuit 130

adapted to be actuated in response to energization thereof, a primary winding on said core connected in said electrical circuit, a secondary winding on said core, means for producing current variations in said primary circuit sufficient to cause actuation of said armature and means for retaining said armature in its actuated condition, said means including an electron discharge device connected in circuit with said auxiliary winding.

8. In a railway signaling system, a primary circuit mounted upon a vehicle and energized from a source of alternating current, a secondary circuit arranged upon the track and positioned to be in inductive relation with said primary circuit and adapted to vary the current flowing therein when the vehicle passes over the track, means adapted to be operated from one condition to a different condition in response to said variation, means including a normally inactive electron discharge device for retaining said last means in said different condition after said secondary circuit is passed, and means responsive to said variation for rendering said discharge device active.

In witness whereof, we have hereunto set our hands this 6th day of September, 1927.
